UNITED STATES PATENT OFFICE.

BENJAMIN TALBOT, OF MIDDLESBROUGH, ENGLAND.

INGOT-MOLD FOR THE MANUFACTURE OF STEEL.

1,279,037.

Specification of Letters Patent. Patented Sept. 17, 1918.

Application filed March 13, 1918. Serial No. 222,182.

To all whom it may concern:

Be it known that I, BENJAMIN TALBOT, a subject of the King of Great Britain, residing in Middlesbrough, England, have invented certain new and useful Improvements in Ingot-Molds for the Manufacture of Steel, of which the following is a specification.

10 This invention relates to an improvement in ingot molds used in the manufacture of steel, whereby an improvement is also brought about in the steel itself cast in such improved mold.

15 It is known that in that form of ingot mold known as a brick topped mold the steel ingot cast in same will have the piped and segregated area located almost entirely in the top part of the ingot which is surrounded by the interior bricked lining, so 20 that the main part of the ingot below the bricked part is thereby improved in quality. In a large works, however, the bricking and keeping in repair of the brick topped sections of ingot molds becomes a serious item, 25 as such bricked topped ingot mold will only run a few heats without requiring renewal of the bricked portion. Moreover, unless very special care is taken in bricking, the joints of the bricks prevent the ready stripping of the ingot.

30 In lieu of having a brick topped mold it has been proposed to place an annular iron receptacle on top of the mold, and before or directly after casting to fill the annular space or chamber with liquid slag or other suitable heated body, such for instance as sand, to about the level of the molten metal upon the top of which, or upon a metal top to the mold, further liquid slag or sand is run. In this proposed arrangement much 35 of the upper portion of the ingot is in contact with metal and not with the slag or brick work, and the piping is removed only to a limited extent while according to the 40 present invention the above drawbacks are removed, and at the same time an appreciable improvement in the position of the piped cavity in the ingot itself is secured, which tends to bring about a lessened waste 45 in the crop discard obtained after rolling.

50 According to this invention, instead of lining the upper part of the ingot mold with bricks or rammed gunister, I take an ingot mold, recessed in the upper portion, and

after arranging inside such mold a suitable 55 core, preferably of iron, supported from the upper part of the ingot mold and fitting closely into the interior of the mold at the point where the recessed part of the mold commences, I run molten slag into the space 60 thus formed between the recessed walls of the mold and the central core. When the slag has set, I release the interior core, and allow it to fall, thereby leaving the ingot mold with the upper recessed portion lined 65 with the slag for any required depth and thickness. If the taper on the core permits, it can of course be withdrawn from the top after the slag has set, but in either event the core is removed before the metal is cast. 70

The slag I always prefer to use is blast furnace slag, not too high in lime, but good results can be obtained from the slag obtained from the open-hearth furnace itself especially from acid open-hearth furnaces. 75 The ingot molds, with the central core held in position may be conveniently run on cars under the slag spout at the blast furnace plant, or the slag may be stored in a liquid condition in a heated receptacle. 80

In steel works, which have not a supply of suitable liquid slag available, the invention may be carried out by casting or molding from the solid slag a top of dimensions suitable to fit into the recess in the ingot 85 mold and such casting may be either in one piece or in suitable sections, and may be placed when cold into position in the ingot mold. To strengthen the slag casting, steel turnings or other form of iron or steel can 90 be introduced into the mass during casting.

In cases in which the steel ingot is cast with the larger end of the ingot uppermost it is always preferable for the slag head to be separate from the mold, so that the head 95 can be pulled off the top of the ingot, so as to enable the ingot to be readily withdrawn from the mold.

One of the advantages due to the use of this slag top is that a small quantity of the 100 slag is liquefied from the face of the slag top; this liquid slag floats on the top of the steel and thus causes the steel to remain liquid in the center and the segregation of the impurities such as sulfur and phosphorus (and carbon) to be brought nearer to the actual top of the steel ingot, thus decreasing the area of the segregated portion 105

and localizing this segregated area into one spot where it can be treated by suitable means.

In order to bring about a still greater differentiation of heat between the slag top portion of the ingot and the portion surrounded only by the iron mold a thick cover plate to the mold may be provided and made preferably of blast furnace or other slag cast separately. This slag cover slightly melts owing to the heat of the steel, and tends to keep the slag mold in good condition.

The accompanying drawings illustrate examples of molds according to the invention. Figure 1 is a central vertical section and Fig. 2 a plan of a mold with a core of rectangular cross section. Fig. 3 is a plan of an otherwise similar mold but in which the core is of circular cross section.

A is the iron casing of the ingot mold, B is an iron core, C a recess or channel formed between an enlargement D provided at the upper end of the casing and the core B and into which recess molten slag is poured when the core is in position, or a casting molded top may be provided to fit the recess as explained above. E is a metal cover plate and F an opening through which liquid slag can be introduced into the recess C. The lower end of the core B fits in the inside of the case slightly below the enlarged top D. The core

is supported by bars placed through holes G provided in the core and resting on the top of the mold.

Having thus described the nature of the said invention and the best means I know of carrying the same into practical effect, I claim:

1. An ingot mold comprising an iron casing, in combination with a removable central core with relation to which said casing is spaced to form a channel around said core, and a lining of slag in said channel.

2. An ingot mold comprising an iron casing having an enlarged top, in combination with a removable central core with relation to which said enlarged top is spaced to form a channel around said core, and a lining of slag in said channel.

3. An ingot mold comprising an iron casing, in combination with a removable central core with relation to which said casing is spaced to form a channel of approximately rectangular cross section around said core, and a lining of slag in said channel.

In witness whereof I have signed my name to this specification in the presence of two subscribing witnesses.

BENJAMIN TALBOT.
